UNITED STATES PATENT OFFICE.

JAMES B. EADS, OF ST. LOUIS, MISSOURI.

IMPROVEMENT IN OPERATING ORDNANCE.

Specification forming part of Letters Patent No. 41,611, dated February 16, 1864.

To all whom it may concern:

Be it known that I, JAMES B. EADS, of the city and county of St. Louis, and State of Missouri, have invented certain new and useful Improvements in Operating Heavy Ordnance in Fortifications or on Vessels of War; and I do hereby declare the following to be a full, clear, and exact description of the same, reference being had to the accompanying drawings, making a part of this specification, in which—

Figure 1 represents a side-view of a gun and the mechanism for operating it. Fig. 2 represents a top plan, and Fig. 3 represents a vertical section of the same. Fig. 4 represents a table for turning the gun horizontally upon, and a device for locking it in proper position.

Similar letters of reference, where they occur in the several figures, denote like parts in all the drawings.

My invention consists, first, in certain mechanism for elevating and lowering and running a gun into or out of a port on vessels of war, or working them in a casemate on land or permanent fortifications, said mechanism being operated by steam, water, or air as a first moving power; and my invention consists, secondly, in making the pivot, upon or around which the base or platform moves that carries and sustains the gun, and mechanism for operating it, hollow, for the purpose of admitting or of admitting and discharging the steam, air, or water used for operating the gun.

To enable others skilled in the art to make and use my invention, I will proceed to describe the same with reference to the drawings.

The base or platform A, upon which the gun and mechanism that operates it are placed, is pivoted at its forward end by a hollow bolt or pivot, B, and close up to the side of the vessel or casemate C. The after portion of this base or platform may have friction-wheels in it, that may run upon circular ways upon the deck or gun floor D, so that the breech of the gun may be readily moved to the right or left, and turning upon the hollow bolt or pivot B as a center.

Upon the base or platform A is placed a steam, hydraulic, air, or other gas-cylinder, E, of which F is the piston-rod, the piston of this rod being moved in the cylinder by means of

steam, water, air, or gas introduced through the hollow bolt or pivot B through suitable pipes, chests, valves, ports, &c., of any of the well-known kinds.

On the piston-rod F there is a cross-head, G, on each end of which there is a cogged rack, H, said racks moving in suitable ways or guides, to prevent cramping.

I are pillow-blocks (one only being seen in the section) secured to the base A, to which are pivoted the segmental gears J and the cranks K, said segments and cranks being so attached as to move together. The upper ends of the cranks K are pivoted to slides L, that move longitudinally upon the gun-frame M; and they have, moreover, wrist-pins N in them about midway between their two ends, which wrist-pins work in slots O in the free ends of the levers P, which are pivoted at Q on the forward part of the base A. The levers P have also wrist-pins R upon them, to which one end of the connecting rod or bar S is attached, the other end thereof being attached to the gun-frame at T by a suitable wrist-pin, from which pin a lever, U, extends backward and downward, and is pivoted at its lower end to the pillow-block I at the point V. By this system of levers the gun and its frame are elevated or depressed at their rear, while the point of the gun or muzzle will vary but little from a fixed position in the port, and the outside of the port may thus be but a trifle greater in diameter than the outside diameter of the muzzle of the gun; or, in other words, the muzzle of the gun may fill the port without leaving any space between through which the smallest projectile could possibly pass. When the cross-head G is moved from the cylinder E, the racks H turn the segments J and operate the cranks K, and through the levers and their several connections, as above described, the breech of the gun is elevated, as shown in Fig. 3; and when the cross-head is moved toward the cylinder the breech of the gun and the several parts operating it come down into the position shown in Fig. 1 in black lines, the red lines in said figure representing the gun and some of its parts as elevated.

In grooves W in the side pieces of the gun-frame a block, X, upon which the gun Y is arranged, is moved by means of steam, air, water, or gas working in a cylinder, Z, attached to the

gun-frame, and supplied with its propelling element through a flexible connection or pipe connected with the hollow pivot B, or the steam-pipe connected with B.

a is a piston-rod working in the cylinder Z. This piston-rod is connected to the block or carriage X, while the cylinder is connected to the gun frame or slides, and thus the gun, resting on the block or carriage, may be moved freely and readily on the gun frame or slides to or from the port or casement, as may be desired. There are also air chambers or cylinders b, connected with the block X, in which work piston-rods c, attached to the gun-frame. These air-cylinders and pistons are designed to take the recoil of the gun, and thus relieve the frame from sudden jars.

Upon the block or carriage X is pivoted strongly, as at d, a table, e, upon which, in suitable bearings, f, the gun is hung by its trunnions g. This table e can turn upon its pivot-pin d, for the purpose of easily loading it when drawn in from the port, and when loaded it can be again turned in the direction of the port, to be run out and fired. A spring-latch, h, catching into the notch i in the turning table e, holds the gun in proper position to be run into and out of the port, while the notches j k would catch and hold it at right angles to that line, or nearly so. The latch h, by means of the handle l, may be easily drawn out of its catches, while its spring m will throw it into the first one that comes opposite to it.

I have not described nor shown the levers, valves, chests, &c., for operating the pistons in the cylinders E Z. These, being well known and common, may be applied by any mechanic.

In this arrangement the gun does not vibrate on its trunnions on the gun-carriage; but when run in or out its longitudinal axis is always parallel with the gun-slides.

I have it in contemplation to so modify this general plan as to raise the gun-slides in a level manner, instead of raising the breech ends faster than the other ends, in which case the gun will vibrate on its trunnions, and the muzzle will be retained at a fixed point by suitable devices while the slides or gun-frame is moved up or down horizontally.

Having thus fully described my invention, what I claim therein is—

1. The raising or lowering of the gun slides or frame on which the carriage moves in a line, so as to keep the axis of the gun in a line parallel therewith, and in such manner that the breech and trunnions of the gun are moved up or down, while the muzzle of the gun is kept at nearly a fixed point, for the purpose of giving the necessary vertical range or aim of the gun, and thus obviating the use of a port-hole larger than the muzzle of the gun, substantially as described.

2. The pivoting of the platform A, that carries the gun or guns, and the mechanism for operating it or them, on a hollow pin or pivot, for the purpose of admitting, or of admitting and discharging, the steam, air, water, or other element for operating the mechanism that raises or lowers or moves the gun to or from the port, substantially as described.

JAS. B. EADS.
